LUBRICANT PUMP

Johann Lipinski, Pressbaum, near Vienna, Austria, assignor to Alex. Friedmann Kommandit-Gesellschaft, Vienna, Austria, a firm

Application May 13, 1955, Serial No. 508,287

8 Claims. (Cl. 184—32)

This invention relates to a lubricant pump of that type in which one or several pump units are separately inserted in a pump box and each of said pump units comprises a cylinder and a working piston, which is formed with one or several control ports and is rotatable to control the connection of its working space with the inlet and outlet. In the known pumps of that type in which the pump units are individually inserted in the pump box, these units are flanged to the pump box from the outside. Such constructions are somewhat less expensive than constructions in which groups of pump units are combined to form a block and inserted in the pump box because the pump units for pumps having different numbers of outlets can be manufactured in larger quantities. In the known constructions, however, the economy thus effected is not great because such pump units flanged to the pump casing are of relatively complicated shape and require expensive machining operations.

It is an object of the invention to reduce the cost of such lubricant pumps. The invention is based on the recognition that a considerable simplification in construction is possible just in that type of lubricant pumps in which the control of the working space is effected by the rotation of the working piston and in which for that reason only a single piston and one cylinder are required for each valveless pump unit. The invention resides essentially in that each pump cylinder is formed by a solid of revolution which is of conical shape or provided with a collar in its intermediate zone and which is held against rotation and is clamped by an outlet nipple in a bore which is reduced in conical or stepped form, whereas the intake duct which opens on the outside surface of the cylinder portion facing the interior of the casing is sealed from the discharge duct which opens adjacent to the closed cylinder end and leads into the cavity of said outlet nipple. The formation of the cylinder as a solid of revolution represents the simplest form, which is least expensive as regards machining. This is due to the elimination of the fixing flange for the pump unit and by the provision of a fixing member, i.e. the screw nipple, which is separate from the cylinder. The place where the pump unit is received in the pump box consists only of a bore, which is formed at its inner end with a constriction delimiting the depth of insertion of the cylinder, and at its outer end, e.g., with a thread for the nipple. Thus the machining of the pump box is minimized too. The measure of forming the bore of the pump box for the cylinder with a conical reduction has the advantage compared to the stepped formation, that the cylinder is tightly forced into the outer cone by the nipple and additional sealing members are eliminated. That construction is favourable if the inlet bore of the cylinder is to be tightly sealed against the interior of the pump box as well as against the outside and against the cavity of the outlet nipple, as is required in those types in which the lubricant is sucked into the working space of the piston through a riser and a dripping chamber provided with a sight glass. Since the cylinder lies partly in the outlet nipple the overall

2

length is reduced and the bosses which must be provided in the pump box casting to accommodate the bores receiving the cylinders may be relatively small.

In order to avoid a disturbance of the simple shape 5 enabled by the invention the means required in that type of pump to prevent the rotation of the cylinder and to determine its inserted position may comprise a detachable part, e.g. a pin inserted in the cylinder and engaging a groove in the bore of the pump box, or a ledge affixed to the pump box and cooperating with a surface formed on the cylinder, so that neither the outside surface of the cylinder nor the bore of the pump box has a projecting part which would considerably add to the machining expense.

15 Illustrative embodiments of the invention are shown in the drawing.

Fig. 1 is a sectional view of the pump box and a pump unit of a lubricating pump.

Fig. 2 is a sectional view of the pump box and a pump unit of a lubricant pump of modified construction.

In the embodiment according to Fig. 1, 1 represents the pump box, which has inserted therein the pump units comprising a cylinder 2 and a piston 3. The piston 3 is driven in the usual manner by a ball pin 6 of a tappet 25 rod 7, which is rotatably and axially slidably mounted and is driven to oscillate and axially reciprocate through the intermediary of a ball pin 8, which engages an eccentric bore 9 of a head 10 of the drive shaft 11. The ball pin 6 enters a cavity 4 of the piston head 5. Thus the piston 3 does not only perform a reciprocating conveying movement but also a rotary control movement, in the course of which it connects its working space 14 in the known manner alternately with the inlet bore 12 and the outlet bore 13. 15 represents the setting screw which 35 determines the quantity to be delivered.

The cylinder 2 is formed as a simple solid of revolution, which is provided with a collar 16 in its intermediate zone. That cylinder is inserted in a bore 17 of the pump box 1 and is clamped by the outlet nipple 18 against a shoulder 19 of the bore 17. Since a rotary piston control is employed, the cylinder 2 must be built in and secured in a predetermined position. To this end the cylinder has inserted therein a pin 20, which engages a groove 21 of the bore of the shoulder 19. In the 45 corresponding control position of the piston 3 the lubricant is sucked from the interior 23 of the pump box 1 through a bore 22 of the pump box 1 and the inlet bore 12 into the working space 14.

As the piston 3 is rotated its control groove 24 is connected to the outlet bore 13 so that the piston 3 conveys the lubricant into the outlet nipple 18. To this end the outlet bore 13 leads to a cavity 25 of the outlet nipple 18. As is shown in the drawing the outlet nipple 18 is formed at its inner end as a hollow cylinder 26, which has an external screw thread 27. Thus the cylinder 2 lies partly in the outlet nipple 18, so that the overall length and the length of the bosses 28, 28' provided in the pump box casting can be reduced. A gasket ring 29 is provided between the hollow-cylindrical extension 26 of the outlet nipple 18 and the collar 16 of the cylinder 2 and provides like a stuffing box a seal between the outlet nipple 18 and the cylinder 2 as well as between the said parts and the bore 17. No seal is required between the collar 16 of the cylinder 2 and the shoulder 19 of the bore 17 because the pump unit sucks the lubricant directly from the interior 23 of the pump box 1.

The embodiment according to Fig. 2 differs from the embodiment according to Fig. 1 mainly by the fact that the upper portion of the cylinder 2' is formed with an external cone 30, which is forced into a conical bore 31 of the casing. The cylinder 2' is again clamped in the pump box 1' by the outlet nipple 18 and the outlet bore

13 of the cylinder 2' opens into the cavity 25 of the nipple 18. Contrary to the construction according to Fig. 1 the rotation of the cylinder is prevented by a ledge 32 screwed to the pump box 1' and cooperating with a surface 33 formed on the cylinder 2'.

In this case the supply of the lubricant to the inlet bore 12 of the cylinder 2' is not effected directly from the interior 23 of the pump box 1' but the lubricant is sucked during the intake stroke of the piston 3 through a riser 34, a sight-glass 35 and a bore 36 into the working space 14 of the piston 3. For this reason this embodiment requires a seal between that portion of the periphery of the cylinder in which the suction line 12 opens and the interior 23 of the pump box; that seal is provided by the conical formation of the cylinder and of the bore 31. This eliminates the need for inserting an additional sealing member, the compressibility of which would render the depth of insertion of the cylinder 2 indefinite and prevent an accurate setting of the quantity to be delivered.

I claim:

1. A lubricant pump comprising a pump box, a bore in said pump box, a valveless pump unit inserted in said bore, said pump unit comprising a pump cylinder and a piston reciprocating within the said pump cylinder and a working space in the said pump cylinder, an inlet opening and an outlet opening in the outer surface of the said pump cylinder in axial distance from each other, means for swinging the said piston about its axis, means in the said piston for establishing communication between the said working chamber and the said inlet opening and outlet opening, respectively, when swung into its respective swing positions, the said pump cylinder being formed as a body of revolution, an outlet nipple coaxial with the said piston and pump cylinder clamping the said pump cylinder in the said bore, the said outlet nipple having a cavity, and means for preventing rotational movement of the said pump cylinder in the said bore, sealing means in the middle zone of said bore and pump cylinder effecting a tight seal between said bore and pump cylinder, the said inlet opening being arranged in the part of the said pump cylinder directed inwardly to the said pump box, the said outlet opening being arranged in the outer part of the said pump cylinder and being in communication with the said cavity, the said sealing means being arranged between the said inlet opening and outlet opening and separating the said inlet opening from the said outlet opening.

2. In a lubricant pump as claimed in claim 1, a step in the outer surface of the said pump cylinder and a step in the said bore, the said outlet nipple clamping the said first-mentioned step against the second-mentioned step.

3. In a lubricant pump as claimed in claim 1, a collar in the outer surface of the said pump cylinder and a step in the said bore, the said outlet nipple acting on the said collar and clamping the said collar against the said step, the said sealing means constituted by a packing arranged between the said outlet nipple and the said collar.

4. In a lubricant pump as claimed in claim 1, the said pump cylinder having a conical outer surface converging to its inner end and the said bore being conical converted to the interior of the said pump box, the conical surfaces forming the said sealing means.

5. In a lubricant pump as claimed in claim 1, the said means for preventing rotational movement of the said cylinder comprising a detachable part.

6. In a lubricant pump as claimed in claim 1, a pin inserted in the said pump cylinder and an axial groove in the said bore, the said pin engaging the said groove and forming the said means for preventing rotational movement of that pump cylinder.

7. In a lubricant pump as claimed in claim 1, a ledge fixed on the said pump box and a flat surface formed on the outer surface of the said pump cylinder, cooperating with the said ledge, the said ledge and flat surface forming the said means for preventing rotational movement of the said pump cylinder.

8. In a lubricant pump as claimed in claim 1, a riser connecting the interior of said pump box to the said inlet opening and means for sealing the surface zone of the said cylinder which contains the said inlet opening, against the interior of the pump box and against said outlet opening.
